(57) CLAIM

The ornamental design for a switch, substantially as shown and described.

DESCRIPTION

FIG. 1 is a top plan view of a switch, showing my new design, and

FIG. 2 is a bottom view thereof,

FIG. 3 is a front elevation view thereof,

FIG. 4 is a rear elevation view thereof,

FIG. 5 is a left side elevation view thereof,

FIG. 6 is a right side elevation view thereof; and,

FIG. 7 is a top perspective view thereof.

The details of the internal components of the switch, shown in dotted lines in FIG. 3, forms no part of the claimed design.
